UNITED STATES PATENT OFFICE.

WILLIAM E. PRINDLE, OF MANITOWOC, WISCONSIN.

ROTARY DRIER.

1,126,077.

Specification of Letters Patent.

Patented Jan. 26, 1915.

Application filed August 6, 1913. Serial No. 783,248.

To all whom it may concern:

Be it known that I, WILLIAM E. PRINDLE, a citizen of the United States, and residing at Manitowoc, in the county of Manitowoc and State of Wisconsin, have invented certain new and useful Improvements in Rotary Driers, of which the following is a full, clear, and exact description.

My invention relates to the class of rotary driers; and pertains more particularly to that type of drying apparatus designed for use in drying pulp, or other material, possessing a large degree of moisture; and relates in an especial sense to an improved interior arrangement for effectively drying material of this general character.

One object of the invention is to provide a novel drier arrangement wherein highest temperatures are effectively employed to act upon material in its wettest stage, with the application of gradually decreasing temperatures to the material as it correspondingly parts with its moisture, whereby the material is discharged as an uniformly dried product. Another object is the provision in a drier of this character of inter-communicating longitudinal chambers, whereby the heating medium has an extended transverse and free circulation through all of the chambers.

A further object is the provision of an improved means for cascading and stirring up the material, and wherein the degree of cascading and stirring is increased by a particular and novel arrangement of members as the material correspondingly parts with its moisture. A still further object is the provision of means in a rear drier chamber adapted to prevent dry and light particles from being drawn therefrom by suction means positioned adjacent thereto.

These, together with such other objects as may hereinafter appear, or are incident to my invention, I attain by means of a construction illustrated in preferred form, wherein:

Figure 1 is a vertical longitudinal section through a drier embodying my idea of means;

Figures 2, 3 and 4 are transverse sections taken through the drying portions F, G,

and H on the lines II-II, III-III, IV-IV, respectively, and illustrating diagrammatically the preferred interior arrangement in these said portions;

55

Figure 5 represents a section taken transversely through the expansion or dust chamber D; and,

Figure 6 is an enlarged showing of Figure 4, illustrating more clearly certain details of construction omitted therein for reasons of lucidity.

In carrying out my invention, I provide a tubular drier shell A communicating at its feed or front end with a suitable source of heat, as the furnace chamber indicated by B, through the stationary connecting member C, about whose peripheral edge 4 the said front end is adapted to rotate. The shell receives rotary movement through the gears 5 and 6, the latter being connected with any suitable source of power, and is further provided with tires 7 formed thereon which move on rollers 8, as is usual in driers of this character.

75

Preferably the shell A is disposed at an inclination to the horizontal, the rear or discharge end being lower than the feed end and rotatably received at 8^a in the front wall of an expansion or dust chamber D, 80 which latter incloses the said rear end. The chamber D communicates with an exhaust fan E, through an opening 9 preferably formed in its rear wall, and has mounted therein the staggered baffle plates 10, 85 whose purpose will be hereinafter described. The chamber is provided with a downwardly and centrally inclined base portion or hopper 11, in the lower portion of which a worm conveyer 12 is mounted to discharge 90 the dried product outwardly through the outlet 13. This conveyer is adapted to be operated by suitable power connections.

A feed member is mounted in the stationary member C, such as the feed spout designated by the numeral 14, and is designed to feed the wet pulp, or the like, on to the helicoidal members 15 which are formed on the inner face of the drier and adjacent to the feed end thereof.

95

An effective arrangement of drier interior parts, is the preferred sectional construction

100

shown in the drawings, and wherein I contemplate the provision of three drier sections or portions, represented by the letters F, G and H, and diagrammatically illustrated in section in Figures 2, 3 and 4. These portions which are disposed in stated order longitudinally within the shell A may be characterized as the front, central, and rear drying sections, respectively.

10 The arrangement within the front section consists in the provision of partitions 16 which extend inwardly and radially from the shell to form longitudinal compartments, the inner ends of which partitions 15 preferably do not meet, whereby the compartments are capable of having inter-communication with each other through their inner passages 17. The passages not only permit an effective cascade of the material 20 within the drier, but in addition thereto provide for a free and extensive circulation of the heated air or gases, so that the material in each compartment may be uniformly dried.

For the purpose of cascading the material 25 as the drier shell rotates, I provide each partition with the lifting blades 18 mounted at intervals thereon, and which have their outer marginal edges bent or flanged inwardly toward the longitudinal axis of the 30 shell as at 19, so that at certain times in the rotary movement of the drier the lifting blades virtually act as retaining shelves for 35 portions of the material; and as such are designed to prevent material from moving *en masse*; tending rather to disintegrate and break up the mass in order that the 40 heated air or gases from the furnace chamber act upon the material in an effective and economical manner. The blades 18 may be conformed to decrease in relative width accordingly as they near the longitudinal 45 center of the drier.

This stated arrangement of partitions with their retaining shelves not only pertains in an exclusive sense to the front drier 50 section F, but continues rearwardly in the shell A as a basis or nucleus for the interior arrangement of the other sections G and H, terminating approximately at the peripheral edge of the latter section. Section G in 55 addition to the said partitions and shelves is provided in each compartment with a central flight or shorter stirring partition 20 having retaining shelves 21 of similar conformation and arrangement to that of the shelves 18.

Similarly, the arrangement of partitions, stirring flights, and combined lifting blades and retaining shelves in the central section 60 G is continued to extend rearwardly as the basis or nucleus of the interior arrangement of rear section H. The latter, in addition to the stated arrangement as in section G, is further provided with the intermediate and shorter stirring flights 22, preferably two

in each longitudinal compartment, each radially interposed between a partition 16 and a central flight 20 as in the manner indicated in the drawings. These intermediate and shorter flights 22 also carry blades or shelves 23, but which are oppositely disposed in staggered or alternate arrangement with respect to adjacent shelves 18 and 21, and further have their flanged marginal edges bent away from the drier axis to confront the said shelves 18 and 21, and thus occupy a position where they substantially overlap.

At the inner terminals of each longitudinal partition is mounted a flanged deflecting 80 plate 24, coöperating therewith and with each other to define the passages 17, and which are adapted to aid in disintegrating the mass as part of it passes through the said passages at predetermined intervals 85 during the rotary movement of the drier.

Referring now more particularly to Figure 6, it will be seen that the several flights are adapted to be maintained rigidly in their 90 intervalled and radial positions by means of the flanged arcuate brace members 25 which are secured to them as in the preferred manner shown, and to the partitions 16. When assembled the braces as a whole are concentric with the drier shell and this arrangement forms a rigid connection which at the same time does not interfere with the drying operation. Furthermore, the inner ends of the several partitions 16 may be braced by rods 26, disposed at intervals of 95 say five feet, which may or may not, as desired, be in turn braced longitudinally by the angle irons 27 disposed in the axial line of the drier shell A.

With the parts in position as herein described, the operation of the drier may be substantially outlined as follows: The beet pulp, for example, is fed into the front end of the drier as it rotates through the feed spout 14 and is carried a relatively short 105 distance rearwardly by the helicoidal members 15 to the front drier section F, aided somewhat by the inclination of the drier and the suction induced by the fan. At this point the pulp contains practically 110 80% moisture, and is first cascaded in that portion of the drier wherein highest temperatures constantly prevail, inasmuch as the feed end is in communication with the 115 furnace chamber B, as already set forth.

As the material progresses rearwardly it gradually parts with its moisture, and passing through the section F enters the central section G where it is subjected to slightly lower temperatures, but receives a certain 125 amount of necessary stirring and a more effective cascading by reason of the additional members provided for that purpose in this section. Similarly, in progressing farther in a rearwardly direction, the pulp, 130

which has parted with the greater percentage of its moisture, reaches the larger rear section H, wherein it is subjected to reduced temperatures but also to the maximum degree of stirring and cascading, until it reaches the open rear end where it gravitates onto the conveyer in the chamber D, by which it is discharged through the outlet 13 as an uniformly dried product.

From the description made, it will be apparent, that the material in its wettest stage is subjected to the highest temperatures, and as it gradually parts with its moisture is acted upon by gradually decreasing temperatures and velocities, and that the extent of stirring and cascading is correspondingly increased as the material get drier. The product on reaching the discharge end of the drier shell is dry and light, and is retained in the chamber by the baffle members disposed therein to prevent the dried product from being drawn out by the exhaust member E.

Another advantage incident to the provision of the expansion chamber is that the flow of the gases is retarded, facilitating the deposit of the lighter particles which ordinarily would be drawn out.

The entire arrangement is very effective and practical and lends itself to the construction of a durable and reasonably cheap drier. There is an entire absence of involved and intricate parts, and as the compartments communicate centrally with each other, there is little opportunity for the material to cake and partially clog up the drier.

I do not intend to restrict myself to the exact arrangement as shown, nor to the precise details of construction as shown, as it is obvious that variations thereof may be made without departing from the spirit and scope of my invention as pointed out in the appended claims.

The essential features, elements and operation of the apparatus, together with its simplicity and other advantages thereof, will be clearly apparent to those skilled in the art.

Having thus described my invention, and illustrated its use, what I claim as new and desire to secure by Letters Patent is the following:

1. In a rotary drier; the combination of a shell, a group of intercommunicating segmental compartments adapted to receive the material to be dried comprising a plurality of radial partitions disposed in said shell to have their convergent inner marginal portions spaced away from each other about the axial line of the shell, and constructed and arranged with reference to each other so as to provide an unobstructed passage way for the travel of the material in a transverse direction between adjacent and oppo-

sitely disposed members of the group, and means for cascading the material in its said travel; substantially as described.

2. In an apparatus of the class described, the combination of a rotary drier shell, a series of inter-communicating segmental compartments disposed therein to receive the material to be dried comprising radial partitions extending toward the axis of the shell but terminating short thereof in spaced relation to provide an unobstructed passage way adjacent the axial line of the shell, said passage way forming a means of direct communication between members of the compartment series for the travel of the material therethrough as the shell rotates, and means disposed in said compartments with reference to said passage way for cascading the material during its travel from one compartment to the other.

3. In an apparatus of the character described, the combination of a drier shell communicating with a source of heat adjacent its front end and having a feed member, an expansion chamber inclosing the discharge end of the shell, an exhaust member connected with said chamber, and oppositely disposed baffle members extending transversely of the chamber and interposed between the discharge end of the shell and the inlet of the exhaust member.

4. In a drier, a drier shell communicating at its front end with a source of heat, a feed member at the front end, means to induce a flow of heated air rearwardly through the shell comprising an expansion chamber and an exhaust member connected therewith, said expansion chamber inclosing the open rear end of the shell and provided with a hopper bottom, and a discharge outlet and a discharging means mounted in the hopper bottom, and adapted to deliver the dried material to said discharge outlet substantially as described.

5. In an apparatus of the character described, the combination of a drier shell adapted to receive the material to be dried and to communicate with a source of heat, an exhaust member therefor, an expansion chamber interposed between the exhaust member and the discharge end of the shell, said expansion chamber being provided with a discharge passage and a discharge outlet, and a baffle means extending transversely of the chamber and disposed with reference to said passage substantially as and for the purpose set forth.

6. In a drier, the combination of a drier shell adapted to receive the material to be dried and communicating with a source of heat, an expansion chamber inclosing the discharge end of the drier and formed with an exhaust opening, said expansion chamber being provided with a longitudinal discharge passage, and a discharge outlet, a

4
baffle means interposed between the discharge end of the drier and the said exhaust opening and disposed transversely of said passage, and a discharging device located in said discharge passage and adapted to deliver to said outlet.

In testimony whereof I have hereunto

signed my name in the presence of the two
subscribed witnesses.

WILLIAM E. PRINDLE.
